3 Sheets-Sheet 2

<img alt="Technical drawing of a mechanical assembly, likely a component of an inverter, showing various parts labeled with numbers 1 through 74. The drawing includes a central vertical column with horizontal plates, a central horizontal plate with a central hole, and various connecting rods and supports. Labels include 1, 18, 2, 3, 3a, 6, 6a, 7, 7a, 8, 8a, 10, 16, 19, 20, 22, 23, 24, 25, 26, 30, 30a, 31, 32, 33, 34, 35, 36, 37, 38, 39, 40, 41, 42, 43, 44, 45, 46, 47, 48, 49, 50, 51, 52, 53, 54, 55, 56, 57, 58, 59, 60, 61, 62, 63, 64, 65, 66, 67, 68, 69, 70, 71, 72, 73, 74, 75, 76, 77, 78, 79, 80, 81, 82, 83, 84, 85, 86, 87, 88, 89, 90, 91, 92, 93, 94, 95, 96, 97, 98, 99, 100, 101, 102, 103, 104, 105, 106, 107, 108, 109, 110, 111, 112, 113, 114, 115, 116, 117, 118, 119, 120, 121, 122, 123, 124, 125, 126, 127, 128, 129, 130, 131, 132, 133, 134, 135, 136, 137, 138, 139, 140, 141, 142, 143, 144, 145, 146, 147, 148, 149, 150, 151, 152, 153, 154, 155, 156, 157, 158, 159, 160, 161, 162, 163, 164, 165, 166, 167, 168, 169, 170, 171, 172, 173, 174, 175, 176, 177, 178, 179, 180, 181, 182, 183, 184, 185, 186, 187, 188, 189, 190, 191, 192, 193, 194, 195, 196, 197, 198, 199, 200, 201, 202, 203, 204, 205, 206, 207, 208, 209, 210, 211, 212, 213, 214, 215, 216, 217, 218, 219, 220, 221, 222, 223, 224, 225, 226, 227, 228, 229, 230, 231, 232, 233, 234, 235, 236, 237, 238, 239, 240, 241, 242, 243, 244, 245, 246, 247, 248, 249, 250, 251, 252, 253, 254, 255, 256, 257, 258, 259, 260, 261, 262, 263, 264, 265, 266, 267, 268, 269, 270, 271, 272, 273, 274, 275, 276, 277, 278, 279, 280, 281, 282, 283, 284, 285, 286, 287, 288, 289, 290, 291, 292, 293, 294, 295, 296, 297, 298, 299, 300, 301, 302, 303, 304, 305, 306, 307, 308, 309, 310, 311, 312, 313, 314, 315, 316, 317, 318, 319, 320, 321, 322, 323, 324, 325, 326, 327, 328, 329, 330, 331, 332, 333, 334, 335, 336, 337, 338, 339, 340, 341, 342, 343, 344, 345, 346, 347, 348, 349, 350, 351, 352, 353, 354, 355, 356, 357, 358, 359, 360, 361, 362, 363, 364, 365, 366, 367, 368, 369, 370, 371, 372, 373, 374, 375, 376, 377, 378, 379, 380, 381, 382, 383, 384, 385, 386, 387, 388, 389, 390, 391, 392, 393, 394, 395, 396, 397, 398, 399, 400, 401, 402, 403, 404, 405, 406, 407, 408, 409, 410, 411, 412, 413, 414, 415, 416, 417, 418, 419, 420, 421, 422, 423, 424, 425, 426, 427, 428, 429, 430, 431, 432, 433, 434, 435, 436, 437, 438, 439, 440, 441, 442, 443, 444, 445, 446, 447, 448, 449, 450, 451, 452, 453, 454, 455, 456, 457, 458, 459, 460, 461, 462, 463, 464, 465, 466, 467, 468, 469, 470, 471, 472, 473, 474, 475, 476, 477, 478, 479, 480, 481, 482, 483, 484, 485, 486, 487, 488, 489, 490, 491, 492, 493, 494, 495, 496, 497, 498, 499, 500, 501, 502, 503, 504, 505, 506, 507, 508, 509, 510, 511, 512, 513, 514, 515, 516, 517, 518, 519, 520, 521, 522, 523, 524, 525, 526, 527, 528, 529, 530, 531, 532, 533, 534, 535, 536, 537, 538, 539, 540, 541, 542, 543, 544, 545, 546, 547, 548, 549, 550, 551, 552, 553, 554, 555, 556, 557, 558, 559, 560, 561, 562, 563, 564, 565, 566, 567, 568, 569, 570, 571, 572, 573, 574, 575, 576, 577, 578, 579, 580, 581, 582, 583, 584, 585, 586, 587, 588, 589, 590, 591, 592, 593, 594, 595, 596, 597, 598, 599, 600, 601, 602, 603, 604, 605, 606, 607, 608, 609, 610, 611, 612, 613, 614, 615, 616, 617, 618, 619, 620, 621, 622, 623, 624, 625, 626, 627, 628, 629, 630, 631, 632, 633, 634, 635, 636, 637, 638, 639, 640, 641, 642, 643, 644, 645, 646, 647, 648, 649, 650, 651, 652, 653, 654, 655, 656, 657, 658, 659, 660, 661, 662, 663, 664, 665, 666, 667, 668, 669, 6610, 6611, 6612, 6613, 6614, 6615, 6616, 6617, 6618, 6619, 6620, 6621, 6622, 6623, 6624, 6625, 6626, 6627, 6628, 6629, 6630, 6631, 6632, 6633, 6634, 6635, 6636, 6637, 6638, UNITED STATES PATENT OFFICE.

ABRAHAM NOVICK, OF BROOKLYN, NEW YORK, ASSIGNOR TO F. L. SMITH MACHINE COMPANY, INCORPORATED, OF NEW YORK, N. Y., A CORPORATION OF NEW YORK.

ENVELOPE MACHINE.

Application filed September 15, 1921. Serial No. 500,796.

This invention relates to envelope machines and particularly to that class thereof which is adapted for assembling and folding together an envelope blank and a lining 5 thereof. The object of my improvements is to provide a machine of the class specified of simple construction and which through the overlapping of the timing of several moving parts permits a high speed of operation 10 while maintaining accuracy of result.

With these ends in view my improvements comprise features which are illustrated in the drawings accompanying this specification as embodied in an envelope machine of 15 the well known plunger type and wherein:

Figure 1 is a longitudinal sectional elevation of so much of an envelope machine as will suffice to adequately illustrate my improvements. The section is taken on line 20 1—1 of Fig. 2. Fig. 2 is a plan view corresponding with the showing of Fig. 1, those parts above line 2—2 of Fig. 1 being removed to show more clearly the essential features of the mechanism. Fig. 3 is a fragmentary side elevation illustrating a detail of my improved machine. Fig. 4 is a sectional elevation similar to that of Fig. 1, but showing the parts in different relative positions. Figs. 1, 2 and 4 are to one scale and 30 Fig. 3 is to a much larger scale.

The machine of the present invention is particularly directed to assembling the two portions or blanks of paper which when assembled are folded into a lined envelope. 35 For this purpose the lining blank is but slightly smaller than the envelope blank, and preferably overlaps gummed portions of the envelope blank for securing the lining in place.

Briefly, in the machine of the present invention, the stack of envelope blanks, the stack of lining blanks and the folding box comprise three stations and are arranged sequentially in one line, so that the envelope blank after being taken from the top of the stack is advanced, with the exception of an instantaneous dwell at the lining station, continuously in one direction to the folding box. The envelope blank is lifted from the 40 top of the stack of blanks by the usual vertical reciprocating gummer-pickers, and is stripped off and dropped onto a horizontally reciprocating conveyor which is introduced below the blank just before the blank is 45 stripped from the pickers. At the same time

a picker, preferably pneumatic, lifts the top lining blank from its stack, and the gummed envelope blank passes thereunder, pausing just long enough to receive the lining blank which is delivered thereon by the descent of 50 the lining picker. Coincident with the advancement of the envelope blank to the lining station, reciprocating grippers move horizontally toward the lining station from a direction opposite to the direction of travel 55 of the envelope blank, grip the leading edge of the now duplex blank and carry it forward in its previous direction of travel to the folding box. The coincident operation of several of the described mechanisms 60 greatly reduces the elapsed time of blank movement from stack to folding box, without increasing the liability to derangement of blank positioning during said movement.

Directing attention now more particularly 65 to the drawings, the stack of envelope blanks 3 is supported on bracket 4 of vertical slide 5 and which slide is moved upwardly from time to time to keep the top of the stack at a requisite height to be engaged by the pickers, by known means not shown. Above said stack and mounted for vertical reciprocation toward and from the top of the stack are 70 gummer-pickers 6, 7 and 8. These pickers are preferably mounted for horizontal adjustment on cross-bar 9 fixed to vertical slide 80 10. Said slide is moved up and down at predetermined times by lever 11 pivoted at 12 on the machine frame. One end of said lever is connected by link 13 to cross-head 14 of slide 10 and the other end is operatively connected by rod 15 to an actuating cam not shown. Gum is supplied from time to time to the lower faces of pickers 6, 7, 8, when 85 they are in their upper positions of Fig. 1 by the usual reciprocating gum rolls, not shown. Directly above the top of stack 3 is 90 horizontally reciprocating carrier 16 mounted for movement lengthwise the machine in opposite guides 17, 18. This carrier not only transports the envelope blank to the lining station but at that station acts as a table for supporting the blank during the application 95 thereon of the lining blank, and receives the pressure of the lining picker in such application. Near the left hand end of said carrier are a pair of spaced apart hooks 19, 20 for 100 engaging the contiguous edge of the envelope blank 3^a when that blank is stripped off the pickers by stripping plate 21 and for 105 110

insuring the retention of said blank on the carrier when that carrier moves forwardly to the right from the position of Fig. 1.

For moving said carrier 16, the rear edge thereof, Fig. 1, upper edge in Fig. 2, is provided with a forwardly reaching arm 22 terminating in ear 23 and to which ear is pivotally attached one end of link 24. The other end of said link is pivotally attached to the free end of lever 25 fixed to shaft 26 in the lower part of the machine. Said shaft 26 may be oscillated at predetermined times to move carrier 16 from the position of Fig. 1 to that of Fig. 4 and back again, by the usual cam means not shown. The stack of lining blanks 30 is disposed in the line of travel of carrier 16, the top of said stack lying just below the path of the carrier. Also said stack 30 is located as near envelope blank stack 3 as the blank handling mechanisms will permit, so as to afford the minimum amount of travel of the envelope blank to the lining station.

Said stack of lining blanks is supported on table 27 of vertical slide 28 and which slide is moved upwardly from time to time to keep the top of the stack at a requisite height to be engaged by picker 29, by known means not shown. Above said stack, fixed to plunger 31, mounted for vertical reciprocation is said picker 29. Plunger 31 is tubular and picker 29 is of hollow construction, having in its bottom face openings 32, to present a suction face to the topmost blank of the stack. The air is exhausted from said plunger and picker from time to time as required through pipe 33 connected with an exhaust pump of known character and the exhaust is governed by known means, neither of which are shown. For raising and lowering plunger 31, collar 34 thereof is connected by link 35 with one end of lever 36 pivoted at 37 on the machine frame. The other end of said lever is operatively connected by rod 38 to an actuating cam not shown. For preventing the displacement of envelope blank 3^a on its carrier 16 when that carrier pauses at the lining station, one or more oscillating fingers, one of which 39, is shown, are provided. Said finger 39 is pivoted at 40 on the machine frame and is oscillated from time to time from a suitable cam, not shown, rod 41 operatively connecting said lever and cam. The other end 39^a of said finger is adapted and actuated for swinging into the path of said blank contiguous to its leading edge, when in its lining receiving position, and just before the blank reaches such position, Figs. 2 and 4.

In line with the envelope blank stack and the lining blank stack and beyond the lining blank stack as short a distance as is consistent with the necessary space for collateral mechanism, is folding box 42 of known construction. Suffice it to state that

said box is of rectangular inner conformation and therebelow is provided with the usual folding wings as 43, 44 actuated by known means not shown. Above said folding box is reciprocating plunger 45 adapted and actuated by known means not shown, to descend and push into said folding box the assembled envelope and lining blanks when delivered in place and then to withdraw to repeat the operation. 75

For receiving the assembled envelope and lining blanks from carrier 16 at the lining station and advancing those assembled blanks to the folding station, reciprocating means, operating in the same line as carrier 16 but from the opposite direction are provided. Preferably these means comprise a pair of spaced-apart parallel slides 46, 47 traveling in guides 48, 49 respectively fixed to the machine frame. Those ends of said slides nearer the lining station are provided with sheet gripping means. As these and other features of said slides are the same for both, a description of slide 47 and its appurtenances will suffice for both. The gripping means on said slide comprises fixed jaw 50 and jaw 51 pivoted thereto at 52. Said pivoted jaw 51 has latch arm 53 for engagement with latch 54 pivoted at 55 to fixed jaw 50. Spring 56 connecting pivoted jaw 51 and latch 54 is efficient for urging said pivoted jaw toward fixed jaw 50 and for urging said latch toward latch arm 53. Said latch arm is provided with cam roll 57 for engagement with fixed cam 58 for opening jaw 51 and latch 54 has pin 59 for engagement with downreaching arm 60. For actuating slide 47, ear 61 thereof is connected by link 62 to the free end of lever 63 fixed to shaft 64 near shaft 26. A similar arm 65 is also fixed to shaft 64 and is similarly connected to slide 46. Shaft 64 is oscillated at suitable times by cam means of known character not shown. 105

For receiving and locating the assembled envelope and lining blanks over the folding box the following means are provided. A reciprocating grid, comprising rails 66, 66, 66, is pivotally connected at 67 to the upper end of lever 68 pivoted at 69 to the frame of the machine. The lower arm 70 of said lever is operatively connected by rod 71 to cam mechanism of known character not shown. This grid is moved in the line of travel of the blanks, to above the folding box for receiving the blanks thereon and then withdrawn, to the position of Fig. 2, to permit plunger 45 to push the blanks into the folding box. Spaced apart a distance sufficient to permit plunger 45 to pass therebetween and disposed parallel with the line of travel of the blank, are opposite hooks 72, 73. Said hooks spring from table 74, onto which the blanks are delivered and their noses project to the left over the path of said blanks and the blanks are delivered under said noses 115 120 125 130

against the body of said hooks. To insure the positioning of said blanks against said hooks a pair of swinging fingers 75, 76 fixed to shaft 77 are provided. Said shaft is 5 mounted for oscillation in bearings fixed to the machine frame above the path of the blanks and said shaft may be oscillated from time to time as required by means of arm 78 fixed to shaft 77. Said arm is operably connected to cam means of known character, not 10 shown, through rod 79, one end of which is pivotally connected to said arm.

The operation of my improved mechanism is as follows: Suitable envelope blanks 3 15 and lining blanks 30 having been supplied to the machine and the respective supports therefor elevated to present the uppermost blank of each stack in position to be engaged by the respective pickers the machine is started. Pickers 6, 7, 8 having been supplied with gum on their lower faces descend onto stack 3, the uppermost blank of which receives the gum from the pickers and adheres to said pickers thereby. Simultaneously 20 with the descent of picker plunger 10, lining blank picker 29 descends idly to engagement with carrier 16 which at that time is thereunder. Then the gummer pickers rise sufficiently to lift the topmost envelope blank 25 to a position just below stripping plate 21. Coincidently lining picker 29 rises sufficiently to permit carrier 16 to reciprocate to the left to the position of Fig. 1 ready 30 to receive the envelope blank then held by pickers 6, 7, 8.

As soon as carrier 16 has passed to the left from under picker 29 that picker descends onto stack 30, the air is exhausted from said picker which thereupon engages 40 the topmost lining blank of the stack and lifts that blank 30^a to the position of Fig. 1, just above the path of carrier 16. In the meantime the gummer pickers rise through stripping plate 21, by which the envelope blank 3^a is stripped off, said blank falling upon carrier 16, Fig. 1. Said carrier then advances to the right hooks 19, 20 thereof engaging the rear edge of the gummed envelope blank and said blank is carried to the lining station. During the advancement of the envelope blank to the lining station, oscillating fingers, as 39, swing down, presenting their lower ends, as 39^a, in the path of the blank, for locating that blank at the lining station. At the same time the opposite grippers, as 50, 51, move to the left to the position of Fig. 4, reaching that position substantially simultaneously with the arrival 50 of the envelope blank from the opposite direction. Also at the same time plunger 29, bearing lining blank 30^a on its lower face, descends and presses that blank onto the envelope blank against the resistance of carrier 16, the edges of the lining blank overlapping gummed portions 7^a, 7^b of the envelope.

lope blank and slightly overlapping the inner edges of gummed portions 6^a and 8^a. Thereupon the locating fingers, as 39, swing upwardly to the position of Fig. 1, to permit the free exit of the now duplex blank from the lining station. Just as the opposite grippers, as 50, 51, reach their positions respectively for engaging the envelope blank at the lining station the outstanding latch pins, as 59, engage the respective downreaching arms, as 60, causing the latches, as 54, to release the movable gripper jaws, as 51, which thereupon close and grip the blank against the fixed jaws, as 50. 75

Immediately after depositing the lining blank on the envelope blank, the suction in picker 29 is cut off and said picker starts at once on its upward movement, thus freeing the duplex blank for removal by grippers, as 50, 51, which already have the envelope blank in their grip. Immediately said duplex blank is freed from the pressure of picker 29, said grippers start on their return movement to the right, conveying the duplex blank to the folding station, Fig. 1. 90

It will be noted that the several mechanisms cooperate to reduce the time of the pause of the envelope blank at the lining station to an almost instantaneous period of time, the carrier 16 delivering the envelope blank at the lining station coincident with the reception of said blank by the reciprocating grippers, as 50, 51, and during that transfer from one conveying means to the other, the lining is applied and the lining plunger retires sufficiently to permit the onward movement of the duplex blank. 95

While the duplex blank is being conveyed from the lining station to the folding station grid 66 moves from the position of Figs. 2 and 4 to the position of Fig. 1 thereby providing a support over the folding box for the reception of the duplex blank. Just prior to the arrival of said grippers, as 50, 51, at the end of their movement to the right their cam rolls, as 57, ride up onto their respective fixed cams, as 58, thereby opening the pivoted jaws away from the fixed jaws, Fig. 1, whereby the duplex blank is freed just after passing under the noses of hooks 72, 73 and just before the envelope blank reaches the bodies of said hooks. Thereupon fingers 75, 76 swing to the right, Fig. 1, and push the envelope blank against the bodies of said hooks, thereby locating said blank over the folding box. Then plunger 45 descends, coincident with the retirement of grid 66 to the position of Figs. 2 and 4, and said plunger pushes the duplex blank into and through folding box 42 and onto folding table 80 where folding wings, as 43, 44, fold the flaps, thus completing the envelope. 115 120 125

While the invention has been described in connection with the assembling of linings 130

with envelope blanks, it will be appreciated, of course, that this use is merely illustrative and that the principle of the invention may be employed for assembling other parts, such as windows, patches and the like with envelope blanks, or in general for assembling any desired pairs of sheets with each other.

Variations may be resorted to within the scope of the invention and parts of the improvements may be used without others.

I claim:

1. In an envelope machine having three stations, the combination of instrumentalities arranged and operating in one line for advancing the envelope blank from the first station to the third station comprising reciprocating means moving in one direction for advancing the blank from the first to the second station, and other reciprocating means, independent of said first means, moving in the opposite direction for receiving the blank from the first reciprocating means and then reversing its direction of travel for continuing the advancement of the blank to the third station.

2. In an envelope machine having three stations, the combination of instrumentalities arranged and operating in one line for advancing the envelope blank from the first station to the third station comprising reciprocating means moving in one direction for advancing the blank from the first to the second station, and other reciprocating means, independent of said first means, moving in the opposite direction for receiving the blank from the first reciprocating means and then reversing its direction of travel for continuing the advancement to the third station, the transfer of the blank from the first reciprocating means to the other reciprocating means being accomplished while the blank is being operated upon at the second station.

3. In an envelope machine having three stations, the combination of a series of instrumentalities arranged in one line for advancing the envelope blank from the first station to the second station and thence to the third station comprising reciprocating means moving in one direction for advancing said envelope blank from the first to the second station, and other reciprocating means, independent of said first means moving in the opposite direction for receiving the envelope blank from the first reciprocating means and then reversing its direction of movement for continuing the advancement of the blank to the third station, said blank remaining in the control of said first reciprocating means until engaged by said second reciprocating means.

4. In an envelope machine having means for supporting a stack of envelope blanks, means for lifting the uppermost blank from the stack, a lining station and a folding sta-

tion, the combination of a series of instrumentalities arranged in one line for advancing the envelope blank from the lifting means to the lining station and thence to the folding station, comprising reciprocating means moving in one direction for advancing said envelope blank from the lifting means to the lining station, and other reciprocating means, independent of said first means, moving in the opposite direction for receiving the envelope blank from the first reciprocating means and then reversing its direction of movement for continuing the advancement of the blank to the folding station.

5. In an envelope machine having means for supporting a stack of envelope blanks, means for lifting the uppermost blank from the stack, a lining station and a folding station, the combination of a series of instrumentalities arranged and operating in one line for advancing the envelope blank from the lifting means to the lining station and thence to the folding station comprising reciprocating means moving in one direction for advancing said envelope blank from the lifting means to the lining station, and other reciprocating means independent of said first means moving in the opposite direction for receiving the envelope blank from the first reciprocating means and then reversing its direction of movement for continuing the advancement of the blank to the folding station, the transfer of the envelope blank from the first reciprocating means to the other reciprocating means being accomplished while the lining blank is being delivered onto the envelope blank.

6. In an envelope machine having means for supporting a stack of envelope blanks, means for lifting the uppermost blank from the stack, a lining station and a folding station, the combination of a series of instrumentalities arranged in one line for advancing the envelope blank from the lifting means to the lining station and thence to the folding station comprising reciprocating means moving in one direction for advancing said envelope blank from the lifting means to the lining station, and the other reciprocating means, independent of said first means, moving in the opposite direction for receiving the envelope blank from the first reciprocating means and then reversing its direction of movement for continuing the advancement of the blank to the folding station, said blank remaining in the control of said first reciprocating means until engaged by said second reciprocating means.

7. In an envelope machine having a lining station and a folding station, the combination of a carrier-table adapted to receive an envelope blank, transport it to the lining station and to there support the blank during the application of the lining blank thereto,

- and other means, independent of the carrier-table, reciprocating in the same line as the carrier-table for continuing the advancement of the blank from the lining station to the 5 folding station.
8. In combination, a folding station, a lining station, means supporting a stack of envelope blanks, means supporting a stack of lining blanks in line with the said folding 10 station, lining station and said stack of envelope blanks, means for transporting one of each of said blanks to the lining station to there unite them, and means for delivering the united blanks to the folding station.
- 15 9. In combination, means supporting a stack of envelope blanks, means supporting a stack of lining blanks, a lining station, a creasing station in line with said stacks of blanks and said lining station, and a carriage for receiving an individual envelope 20 blank and transporting it to the lining station and there supporting it during the application of the lining blank thereto.
10. In combination, means supporting a 25 stack of envelope blanks, means supporting a stack of lining blanks and a folding station, said stacks and station being in line with each other, a lining station adjacent to said stack of lining blanks, means for 30 conveying an individual envelope blank to the lining station, means for applying an individual lining blank to said main blank at the lining station and means for delivering the united blanks to the folding station.
- 35 11. In combination, a folding station, means supporting a stack of envelope blanks, means supporting a stack of lining blanks in line with said folding station and first mentioned stack, means for lifting an individual 40 blank from the first mentioned stack and transferring the same to a position just above said stack of lining blanks, means for lifting an individual lining blank from said stack of lining blanks, holding said lining 45 blank in raised position until the arrival of said first mentioned blank, and then depositing the said lining blank thereon, and means for transferring the united blanks to the folding station.
- 50 12. In combination, means supporting a stack of lining blanks, a folding station, means supporting a stack of envelope blanks in line with said folding station and the first stack of blanks, reciprocating means for lifting the uppermost envelope blank from the 55 stack of said blanks, reciprocating means adapted to receive said blank and transport it to a position just above the said stack of lining blanks, reciprocating means to lift the up-
- permost lining blank from the stack of said blanks and to deposit said lining blank on said envelope blank, and means for engaging the united blanks and transporting them to the folding station. 60
13. In combination, a lining station, means supporting a stack of lining blanks under said lining station, a folding station, means supporting a stack of envelope blanks in line with said stations, a reciprocating gummer-picker for lifting the uppermost blank from said stack of envelope blanks, a reciprocating carriage adapted to slide under said gummer-picker when in a raised position and to have the lifted blank deposited on it, and then to transport it to the lining station, a reciprocating pneumatic picker for lifting the uppermost lining blank from the stack of said blanks, and uniting the said blank with the said envelope blank upon the arrival of the latter on the said carriage, and reciprocating gripper means for engaging the united blanks and delivering them to the 70 said folding box. 75
14. In combination, means supporting a stack of lining blanks, a lining station, a creasing station in line with said lining station, a carriage for receiving an individual envelope blank and transporting it to said lining station and there supporting it during the application of the lining blank thereto, and means for taking the duplex blank from said carriage and transporting it to said creasing station. 80 85 90
15. In a machine for assembling plural parts of sheet material, means for supporting a stack of one of such parts, means for lifting the uppermost of said parts from the stack and holding it in elevated position, means for interposing another part between the lifted part and its stack and means for applying the lifted part to the said other part. 95 100
16. In a machine for assembling plural parts of sheet material, means for supporting a stack of one of such parts, means for lifting the uppermost of said parts from the stack and holding it in elevated position, a table for supporting another part to be united with the lifted part, means for moving said table to interpose it together with the supported part between the lifted part and the stack from which such part was lifted, and means for applying the lifted part to the part on said table. 105 110 115

In witness whereof, I hereby affix my signature this 13th day of Sept., 1921.

ABRAHAM NOVICK.
